(57) **CLAIM**

The ornamental design for an intelligent service robot as shown and described.

DESCRIPTION

5. Intelligent service robot

Fig. 5.1 is a front elevation view of an intelligent service robot showing our new design;

Fig. 5.2 is a back elevation view thereof;

Fig. 5.3 is a left side elevation view thereof;

Fig. 5.4 is a right-side view thereof;

Fig. 5.5 is a top plan view thereof;

Fig. 5.6 is a bottom plan view thereof;

Fig. 5.7 is a front, right-side perspective view thereof; and

Fig. 5.8 is a back, right-side perspective view thereof.

The product is used for intelligent service and intelligent companion.
